Primary Examiner — Michael A Maharajh(74) *Attorney, Agent, or Firm* — The Roy Gross Law Firm, LLC; Roy Gross(57) **CLAIM**

The ornamental design for a tissue rejuvenation device, as shown and described.

DESCRIPTION

FIG. 1 is a perspective view of a tissue rejuvenation device, showing my new design;

FIG. 2 is a top view thereof;

FIG. 3 is a left side view thereof;

FIG. 4 is a right side view thereof;

FIG. 5 is a front view thereof; and,

FIG. 6 is a rear view thereof.

The broken lines shown in the figures are for the purpose of illustrating portions of the tissue rejuvenation device, which form no part of the claimed design.
